METHOD OF RECOVERING TRANSURANIC ELEMENTS OF AN ATOMIC NUMBER BELOW 95

Glenn T. Seaborg and Ralph A. James, Chicago, Ill., assignors to the United States of America as represented by the United States Atomic Energy Commission

Application February 11, 1946, Serial No. 646,946

6 Claims. (Cl. 23—14.5)

This invention relates to the concentration of transuranic elements contained in dilute solutions thereof or in mixtures with larger amounts of other metal compounds. The invention is especially concerned with the concentration of compounds of element 93 and element 94 contained in less than millimolar concentrations in solutions derived from neutron-irradiated uranium.

An object of the present invention is to provide a process for concentrating elements 93 and 94 in solutions so dilute as to make impractical the direct recovery of a precipitate consisting solely of insoluble compounds of elements 93 and 94.

Another object of this invention is to provide a multi-stage process for concentrating element 94 in such solutions to an extent sufficient to enable the recovery of a final precipitate of a substantially pure compound of element 94.

A further object of the present invention is to provide a method for concentrating element 94 in mixtures containing ions of element 94 and cations of coprecipitable carrier compounds, whereby the ratio of carrier cation to element 94 may be substantially reduced.

Additional objects and advantages of this invention will be evident from the following description, and the accompanying drawing which sets forth diagrammatically the principal steps of a preferred modification of the invention.

The term "element 94" is used throughout this specification to designate the element having atomic number 94. The designation 94²³⁹ refers to the isotope of element 94 having a mass number of 239. Element 94 is also referred to in this specification, and probably will become known in the art, as plutonium, symbol Pu. Likewise, element 93 means the element having atomic number 93, which is also referred to as neptunium, symbol Np. Reference herein to any of the elements is to be understood as denoting the element generically, whether in its free state, or in the form of a compound, unless otherwise indicated by the context.

The apparent discovery of transuranic elements (element 93 and elements of higher number) was first announced by E. Fermi in 1934. At that time Fermi stated that the bombardment of uranium with neutrons gave beta activities which he attributed to transuranic elements of atomic number 93 and possibly higher. From 1934 to 1938 other workers, notably Hahn and Curie, extended this work. But in 1939, Hahn discovered that the elements which he and others had believed to be transuranic elements were in fact radioactive elements of medium atomic weight produced by the fission of uranium. Hahn's results were subsequently confirmed, and a great many fission products in addition to those first found by Hahn were discovered and identified. Such products were all of lower atomic number than uranium, generally of atomic numbers in the middle of the periodic group; and so far as is now known, prior to about June 1940, no evidence was found to establish the existence of any transuranic element.

However, in June 1940, McMillan and Abelson pub-

2

lished in "The Physical Review," 57, 1185, their discovery that a 2.3-day activity produced by the bombardment of uranium with neutrons was an isotope of element 93, probably 93²³⁹. Although McMillan and Abelson surmised that element 94 would be formed by beta decay of element 93²³⁹, they were unable to produce any evidence of its existence, and did not obtain either 93²³⁹ or 94²³⁹ in pure form or in microscopic amounts, either as the element or as a compound.

10 E. Segre, G. T. Seaborg and J. W. Kennedy, using the methods of McMillan and Abelson, obtained 93²³⁹ admixed with rare earths, proved that 93²³⁹ decayed to 94²³⁹, and measured the radioactive and fission properties of 94²³⁹. Subsequently, neutronic reactors were developed for the production of 93²³⁹ and 94²³⁹ in isolable quantities by a self-sustaining chain reaction of slow neutrons with U²³⁵ and U²³⁸ in natural uranium.

Natural uranium comprises largely isotope U²³⁸, together with about 1/139 as much U²³⁵ and a very much smaller amount of U²³⁴. When this mixture of isotopes, either as metallic uranium or as a uranium compound, is subjected to bombardment by neutrons from an external source, or undergoes a self-sustaining neutronic chain reaction, a number of nuclear reactions take place. 20 Isotope U²³⁸ captures a neutron to form U²³⁹, which undergoes beta decay to form transuranic elements as shown by the following equation:

30 Isotope U²³⁵ undergoes fission, i.e., a breakdown of its heavy nucleus into lighter fragments which are generally very unstable and highly radioactive. Such fragments usually undergo beta-particle disintegration in successive steps, leading ultimately to stable isotopes of higher nuclear charge than the original fragments. The fission of U²³⁵ is predominantly binary, and may be exemplified by the following type of equation:

40 Substantially all of the fission fragments have mass numbers within the range 77-158, although small quantities of isotopes of lower and higher mass numbers may result from unbalanced binary fissions, ternary fissions, or other reactions of infrequent occurrence. A very 45 large majority of the fission fragments comprises a light group of mass numbers 84-106 and a heavy group of mass numbers 128-150.

The various decay products of the initial fission fragment are referred to herein as fission products. These 50 fission products fall within a range of atomic numbers from about 32 to about 64. The fission products from the light group of fragments referred to above have atomic numbers ranging from about 32 to about 46; and the fission products from the heavy group of fragments have atomic numbers ranging from about 51 to 55 about 64.

The various radioactive fission products have half-lives ranging from a fraction of a second to thousands 60 of years. Those having very short half-lives may be eliminated by aging the material for a reasonable period before handling. Those with very long half-lives do not have sufficiently intense radiation to endanger personnel protected by moderate shielding. On the other hand, the fission products having half-lives ranging from a few days to a few years have dangerously intense radiations which cannot be eliminated by aging for practical storage periods. These products are chiefly radioactive isotopes of Sr, Y, Zr, Cb and Ru of the light group and Te, I, Cs, Ba, La, Ce, and Pr of the heavy group.

65 The total amount of 93²³⁹ and 94²³⁹ produced from U²³⁸ in natural uranium by neutron bombardment is a

function of neutron density and of the time of bombardment. Since ^{94}Zr is fissionable under the conditions for fission of ^{235}U , the net yield of ^{94}Zr per unit of time will decrease as the ratio of ^{235}U content to ^{94}Zr content of the mass decreases. For this reason, a neutronic reaction of ^{94}Zr production is suitably terminated when only a fraction of the ^{235}U has been converted to fission products. The reaction mass at this point contains a large amount of ^{238}U , a much smaller amount of ^{235}U , still smaller amounts of ^{93}Zr , ^{94}Zr and fission products, and traces of other products such as UX_1 and UX_2 . By aging such a mass for a suitable period of time, the ^{93}Zr may be substantially completely converted to ^{94}Zr , with simultaneous conversion of the short-lived radioactive fission products to longer-lived or stable isotopes.

The plutonium content of the aged reaction mass will usually be considerably less than 1 percent of the weight of the unreacted uranium, and may even be less than one part per million parts of uranium. The concentration of fission products will be of the same order of magnitude. The separation of plutonium from such a mass involves extraction from the unreacted uranium, decontamination by separating the radioactive fission products, and concentration of the decontaminated material to obtain a product for which a relatively pure plutonium compound can be directly recovered.

Techniques have been developed for extracting plutonium from a solution of neutron-bombarded uranium by means of a carrier precipitate such as bismuth phosphate or lanthanum fluoride. The precipitates thus obtained are substantially free from uranium but contain sufficient fission products to have intense radiations. Similar techniques have also been developed for the decontamination of the extracted plutonium by means of a carrier precipitate. Such methods usually involve alternately carrying plutonium in one state of oxidation with the precipitate, and leaving plutonium in solution in a second state of oxidation while carrying fission products with the precipitate. After decontamination by such methods, the plutonium may be substantially free from dangerously radioactive fission products, but it is still associated in relatively minute amounts with large quantities of a carrier precipitate or with large volumes of solution containing ions of the preceding carrier precipitate.

Solutions of plutonium obtained by the foregoing procedure have such low plutonium concentrations that the direct precipitation of even the most insoluble plutonium compounds is either impossible or wholly impractical. The application of common concentration procedures to such solutions results in concentration of carrier ions as well as plutonium ions, and increases the difficulties of subsequent plutonium separation.

In accordance with the present invention, the plutonium in such solutions may be concentrated by successive use of a carrier, with decreasing ratios of carrier to plutonium, employing carriers having certain characteristics herein-after set forth which make possible this method of operation. The term "carrier" as used herein and in the appended claims signifies a substantially insoluble, solid, finely divided compound capable of ionizing to yield at least one inorganic cation and to yield at least one anion which constitutes an ionic component of a compound containing the ion to be carried and which is not substantially more soluble than said finely divided compound in the solution from which carrying is to be effected. A large number of compounds having these essential characteristics are known to be carriers for plutonium. Only a relatively small proportion of these, however, have the additional properties necessary for use in the present invention.

A suitable carrier for use in the present process comprises a compound containing at least one ion capable of a change in oxidation state or at least capable of easy destruction such that the other carrier ion may be trans-

formed from a substantially insoluble compound into a compound which is substantially soluble in a solution in which the original carrier compound is substantially insoluble. A preferred carrier of this type comprises a compound whose cation, or anion, or both may be oxidized to form a compound which is soluble in a solution from which the carrier may be reprecipitated in its original state of oxidation, again carrying plutonium in its original oxidation state.

Ceric iodate is an example of a carrier whose cation and anion may be reduced simultaneously to form a soluble compound. Thus, cerous iodide may be maintained in solution while effecting a second precipitation of ceric iodate.

Uranous pyrophosphate is an example of a carrier having an oxidizable cation permitting its use in the present process. A uranous pyrophosphate precipitate carrying tetravalent plutonium may be dissolved in hot nitric acid, thereby oxidizing the uranous ion to uranyl ion without oxidizing the tetravalent plutonium. The resulting uranyl nitrate remains in solution even in the presence of the pyrophosphate ion. A second uranous pyrophosphate precipitation may then be made from this solution, using a smaller quantity of uranous ion than in the original precipitate. The second precipitate will again carry the tetravalent plutonium with effective concentration by reduction of carrier-to-plutonium ratio.

Thorium oxalate is an example of a carrier having an oxidizable anion or anion which may be decomposed permitting its use in the present process. A thorium oxalate precipitate carrying tetravalent plutonium may be dissolved in hot nitric acid, thereby oxidizing the oxalate ion to carbon dioxide, or decomposing this ion to carbon dioxide and carbon monoxide without oxidizing the tetravalent plutonium. A second thorium oxalate precipitation may then be made from the resulting thorium nitrate solution. Other carboxylic acid salts of thorium, such as the citrate or tartrate, may be used in similar manner.

Uranous hypophosphate and uranous salts of carboxylic acid, such as uranous oxalate, are examples of carriers whose cations and anions may both be oxidized simultaneously to form soluble compounds. Thus, a uranous hypophosphate precipitate may be oxidized to uranyl orthophosphate, which may be maintained in solution while again precipitating uranous hypophosphate. Similarly, a uranous oxalate precipitate may be dissolved in hot nitric acid to form a solution of uranyl nitrate from which a second uranous oxalate precipitation may be made.

Also, similar results can be achieved by the use of a suitable sulfide, for example, the sulfides of thorium, uranium and the like. When carriers of the above type are used they may be readily decomposed by the addition of an acid, such as nitric or hydrochloric acid.

The specific carriers referred to above are illustrative of the preferred classes of carriers for the present process. It will be apparent to those skilled in the art that there are numerous other carriers which may be solubilized by a change in oxidation state of one or more ions. The choice of a desirable carrier for this process will depend upon the oxidation-reduction potentials of the carrier ions and of the ion to be carried. If these potentials are too close together, it will be difficult to effect selective oxidation or deoxygenation of the carrier ion, or of the ion to be carried, without simultaneously changing the oxidation state of the other ion. For example, if tetravalent plutonium is to be carried by a carrier having a tetravalent cation, it is desirable either to effect highly selective oxidation of the carrier cation, or to oxidize both the plutonium and the carrier cation and thereafter effect highly selective reduction of the hexavalent plutonium to the tetravalent state.

Plutonium has a number of valence states, including +3, +4, +5 and +6. In 0.5-1.0 M. aqueous hydro-

chloric acid, the oxidation-reduction potentials are of the following magnitudes:

$\text{Pu}^{+3} \rightarrow \text{Pu}^{+4} + \text{E}^-$	-0.97 v.
$\text{Pu}^{+4} \rightarrow \text{Pu}^{+5} + \text{E}^-$	-1.11 v.
$\text{Pu}^{+5} + 2\text{H}_2\text{O} \rightarrow \text{PuO}_2^{+2} + 4\text{H}^+ + \text{E}^-$	-0.92 v.
$\text{Pu}^{+4} + 2\text{H}_2\text{O} \rightarrow \text{PuO}_2^{+2} + 4\text{H}^+ + 2\text{E}^-$	-1.015 v.

The Pu^{+5} ion is generally very unstable, and disproportionates to Pu^{+4} and Pu^{+6} . The Pu^{+4} ion is capable of disproportionating to the Pu^{+3} ion and the PuO_2^{+2} ion, and in aqueous hydrochloric acid this disproportionation may take place to a considerable extent. The Pu^{+4} disproportionation is opposed, however, by increase in hydrogen ion concentration and by the presence of ions which tend to complex or otherwise stabilize the Pu^{+4} ion. The effect of additional ions in hydrochloric acid solutions is illustrated by the following potentials for the $\text{Pu}^{+3} \rightarrow \text{Pu}^{+4}$ couple:

1.0 M. HCl	-0.97 v.
1.0 M. HCl-0.1 M. H_3PO_4	-0.80 v.
1.0 M. HCl-1.0 M. HF	-0.53 v.

Generally the anions of slightly ionized acids tend to complex the Pu^{+4} ion to a much greater extent than the anions of highly ionized acids. Thus, Pu^{+4} is only slightly complexed by ClO_4^- , Cl^- , and NO_3^- ; it is complexed to a much greater extent by SO_4^{2-} ; and it is very strongly complexed by PO_4^{3-} , F^- , $\text{C}_2\text{H}_3\text{O}_2^-$, and $\text{C}_2\text{O}_4^{2-}$.

It may be seen from the above discussion that the +3 state (the trivalent ion), the +6 state (the uranyl ion), and the stabilized +4 state (the plutonous ion), are the most important valence states of plutonium. In the present process it is preferred to carry plutonium in the +4 valence state, employing a carrier having a +4 cation. If an oxidizable +4 carrier cation is to be chosen for this purpose, it should have an oxidation potential substantially less positive than the oxidation potential of the $\text{PuO}_2^{+2} \rightarrow \text{Pu}^{+4}$ couple in the particular solution employed. The following are representative potentials for this couple:

1.0 M. HCl	+1.0 v.
1.0 M. HNO_3	+1.1 v.
1.0 M. H_2SO_4	+1.3 v.

It is thus seen that if it is desired to oxidize the carrier cation in hydrochloric acid solution without oxidizing tetravalent plutonium, the carrier cation should have an oxidation potential substantially less positive than +1.0 v. Reference to a table of standard oxidation-reduction potentials such as that of Latimer and Hildebrand in the Handbook of Chemistry and Physics (Chemical Rubber Publishing Co., Cleveland, Ohio), will indicate which carrier cations are suitable for selective oxidation and will also indicate suitable selective oxidizing agents. Thus, the oxidation potential of the $\text{UO}_2^{+2} \rightarrow \text{U}^{+4}$ couple is about +0.4 v., which indicates that tetravalent uranium may easily be oxidized selectively without oxidizing tetravalent plutonium. An oxidizing agent such as the ferric ion, with an oxidation potential substantially above +0.4 v. and substantially below +1.0 v., may be employed to effect selective oxidation of the U^{+4} ion.

It may also be seen that an alternative procedure can be employed in the case of the U^{+4} carrier cation and the Pu^{+4} ion in hydrochloric acid solution. If an oxidizing agent such as $\text{K}_2\text{Cr}_2\text{O}_7$ is used, the oxidation potential is sufficiently high to oxidize Pu^{+4} to PuO_2^{+2} simultaneously with the oxidation of U^{+4} to UO_2^{+2} . In this case, at the conclusion of the oxidation the PuO_2^{+2} may be selectively reduced by means of a reducing agent having a reduction potential substantially more negative than -0.4 v. and substantially less negative than -1.0 v. Hydrogen peroxide and the ferrous iron are suitable reducing agents for this purpose.

Since the oxidation potential of nitric acid is less positive than the oxidation potential of the $\text{PuO}_2^{+2} \rightarrow \text{Pu}^{+4}$

couple in nitric acid solution, and substantially more positive than the oxidation potential of the $\text{UO}_2^{+2} \rightarrow \text{U}^{+4}$ couple, it may be seen that nitric acid constitutes a selective oxidizing agent for the U^{+4} ion. Thus, a precipitate of U^{+4} carrier and its associated Pu^{+4} may be dissolved in hot nitric acid to form a solution of UO_2^{+2} and Pu^{+4} ions, from which the U^{+4} carrier may again be precipitated in diminished quantity.

Although the oxidation-reduction principles of the present invention have been discussed above with particular reference to U^{+4} carriers, it is to be understood that the same general principles apply to the use of other carriers which may be solubilized by a change of oxidation state of cation, anion, or both cation and anion.

Although the carriers in the present process may be employed as preformed finely divided solids, it is preferable to precipitate the carrier in situ since the latter procedure usually permits a lower carrier ratio and results in more quantitative carrying of plutonium. The first precipitation of any carrier in this process may be effected in accordance with the techniques previously used in extraction or decontamination processes. It is generally preferable to effect this precipitation by incorporating the carrier cation in the solution and then adding the anion while agitating the mixture. The techniques for effecting subsequent precipitations of the same carrier will depend upon the ions present in the solution after dissolving the previous precipitate and changing the state of oxidation of one or more of the carrier ions. If neither of the previous carrier ions is present in the new solution, as in the case of uranous oxalate after oxidation, the same technique may be employed in subsequent precipitations of the carrier as was used in the initial precipitation. If one of the ions of the previous carrier remains in the new solution, however, it will usually be necessary to add only the other ion to effect a reprecipitation.

After the precipitation of the carrier in any step of the present process it is desirable to digest the precipitate for a short time before separating it from the supernatant solution. Agitation of the slurry for one-half hour to one hour or longer at the precipitation temperature will usually increase the effectiveness of the carrying. Care should be taken, however not to digest oxidizable precipitates for long periods in solutions of oxidizing acids. Thus, although acid must be heated to effect rapid oxidation of a U^{+4} carrier, it will oxidize such a carrier slowly at room temperature. A U^{+4} carrier precipitated out of nitric acid should not, therefore, be digested for substantially more than an hour before separation from the supernatant solution.

This invention will now be further illustrated by the following specific example:

Example

A dilute solution of plutonium, obtained by separating unreacted uranium and radioactive fission products from a solution of neutron-bombarded uranium, is concentrated by the procedure illustrated diagrammatically in the accompanying drawing.

The plutonium solution, resulting from dissolving a bismuth phosphate carrier precipitate and its associated plutonium in 6 N. hydrochloric acid, comprises about 10,000 liters of solution containing about 2,910 kilograms of bismuth phosphate and about 80 grams of plutonium. This solution is introduced into the first precipitator and about 25 kilograms of $\text{Na}_4\text{P}_2\text{O}_6$ is then added as a saturated aqueous solution. Approximately 27.1 kilograms of $\text{U}(\text{SO}_4)_2$ in the form of a concentrated solution in dilute sulfuric acid is then introduced, while agitating the mixture. The resulting slurry is digested for one hour at 25° C., with continued agitation, and is then transferred to the first centrifuge for separation of the precipitate.

The hypophosphate precipitate is slurried from the centrifuge to the first dissolver and oxidation reactor with sufficient 6 N. nitric acid to form a solution of approximately 300 liters. The slurry is then heated to 70° C. for about one-half hour to effect solution of the precipitate and oxidation of UP_2O_6 to $(UO_2)_3(PO_4)_2$.

The oxidized solution is then transferred to the second precipitator and 750 grams of $Na_4P_2O_6$ is added as a saturated aqueous solution. Approximately 542 grams of $U(SO_4)_2$ in the form of a concentrated solution in dilute sulfuric acid is then added with agitation. The resulting slurry is digested for three-fourths of an hour at 25° C., with continued agitation, and is then transferred to a centrifuge for separation of the precipitate.

The hypophosphate precipitate is slurried from the centrifuge to the second dissolver and oxidation reactor with sufficient 6 N. nitric acid to form a solution of approximately 6 liters. The slurry is then heated for about one-half hour to effect solution of the precipitate and oxidation of UP_2O_6 to $(UO_2)_3(PO_4)_2$. The final solution thus obtained contains about 24.2 grams of $Pu(NO_3)_4$ per liter, which is a sufficiently high concentration to permit subsequent precipitation of an insoluble plutonium compound such as plutonium peroxide without the necessity of coprecipitating a carrier.

The recovery of plutonium by the above procedure, without recycle of supernatant solutions, is about 89 percent of the quantity in the original solution. By recycling the supernatant solution from the last centrifuging operation to the preceding solution step, the recovery may be increased to about 98 percent.

It may be seen that in the above concentration procedure the volume of the final solution is only 0.06 percent of the volume of the original solution, and the ratio of carrier to plutonium in the final solution is only 0.02 percent of the ratio in the original solution.

It is to be understood of course, that the above example is merely illustrative and does not limit the scope of this invention. Other carriers which can be solubilized by a change in oxidation state of one or more ions may be substituted for the particular carrier employed in the example; and the procedure of the example may be modified in numerous respects in accordance with the foregoing description. In general, it may be said that the use of any equivalents or modifications of procedure which would naturally occur to those skilled in the art is included in the scope of the present invention. Only such limitations should be imposed on the scope of this invention as are indicated in the appended claims.

What is claimed is:

1. A process of separating and concentrating tetravalent values of transuranic elements of an atomic number below 95 contained in an aqueous solution, comprising incorporating a first carrier selected from the group consisting of uranium (IV) hypophosphate, uranium (IV) pyrophosphate, uranium (IV) oxalate, thorium oxalate, thorium citrate, thorium tartrate, thorium sulfide and uranium (IV) sulfide in said solution whereby said transuranic values are precipitated on said first carrier; separating the transuranic values-containing carrier from the solution; adding nitric acid to said carrier; heating the mixture of carrier and nitric acid whereby the carrier is converted to nitrate, the transuranic values are converted to nitrate of the tetravalent state and the nitrates are dissolved in the nitric acid; incorporating a second carrier in the nitric acid solution, said second carrier being chemically identical with said first carrier and the amount of said second carrier being smaller than the amount of said first carrier, whereby said transuranic values are carried on said second carrier; and separating said second carrier from the solution.

2. The process of claim 1 wherein the transuranic values are plutonium values.

3. The process of claim 1 wherein said carriers are incorporated by separately adding to the solution the cation and the anion, each in the form of a water-soluble compound.

5. The process of claim 1 wherein the second carrier is allowed to digest for from one-half to one hour prior to the separation from the aqueous solution.

10. A process of separating and concentrating tetravalent plutonium values contained in an aqueous solution, comprising incorporating a first carrier selected from the group consisting of uranium (IV) hypophosphate, uranium (IV) pyrophosphate, uranium (IV) oxalate, thorium oxalate, thorium citrate, thorium tartrate, thorium sulfide and uranium (IV) sulfide in said solution whereby said plutonium values are precipitated on said first carrier; separating the plutonium-containing carrier from the solution; adding hot nitric acid to the carrier whereby the carrier is converted to nitrate, the plutonium to plutonium (IV) nitrate and the nitrates are dissolved in the nitric acid; incorporating a second carrier in the nitric acid solution, said second carrier being chemically identical with said first carrier and the amount of said second carrier being smaller than the amount of said first carrier, whereby said plutonium values are carried on said second carrier; and separating said second carrier from the solution.

15. A process of separating and concentrating plutonium values present in the tetravalent state in an aqueous acid solution, comprising adding a first portion of an aqueous solution of sodium hypophosphate; adding a first portion of an aqueous solution of uranous sulfate; agitating the mixture obtained thereby at about 25° C. for approximately one hour whereby a precipitate of uranous hypophosphate carrying said plutonium values is formed; separating the precipitate from the solution; adding a first portion of nitric acid to the precipitate; heating the mixture of precipitate and nitric acid to about 70° C. for about 30 minutes whereby the hypophosphate is oxidized to the orthophosphate and the uranyl and plutonium (IV) phosphates are dissolved in the nitric acid; adding a second portion of an aqueous sodium hypophosphate solution and a second portion of an aqueous uranous sulfate solution to the nitric acid solution formed, said second portions being considerably smaller than said first portions previously added, whereby a carrier precipitate forms which contains the plutonium values; digesting the mixture with the carrier precipitate at about 25° C. for about 45 minutes; separating the carrier precipitate from the solution; adding a second portion of nitric acid to the carrier precipitate, said second portion being substantially smaller than said first portion of nitric acid previously added; heating the nitric-acid-containing mixture for about 30 minutes whereby uranyl phosphate and plutonium (IV) phosphate are formed and dissolved and a comparatively concentrated plutonium solution is formed; and precipitating the plutonium values from the concentrated solution.
